Primary Examiner — Bridget L Eland(74) *Attorney, Agent, or Firm* — Birch, Stewart, Kolasch & Birch, LLP(57) **CLAIM**

The ornamental design for a mobile phone, as shown and described.

DESCRIPTION

FIG. 1 is a perspective view of a mobile phone showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a rear perspective view thereof.

The broken lines that are immediately adjacent to the claim, and define unshaded regions, represent the bounds of the claim, while all other broken are directed to environment; the broken lines form no part of the claimed design. ps The broken lines show unclaimed subject matter only and form no part of the claimed design.

1 Claim, 8 Drawing Sheets(56)
